UNITED STATES PATENT OFFICE.

MELVILLE E. PETERS, GEORGE H. FATH, AND ALBERT F. MILLER, OF DENVER, COLORADO, ASSIGNEES TO THE PETERS PATENT RIGHTS COMPANY, OF DENVER, COLORADO, A CORPORATION OF COLORADO.

GUMMED-BLANK WIPER FOR TIGHT AND LOOSE TYPES OF BLANK-WRAPPING WORK.

1,251,817.

Specification of Letters Patent.

Patented Jan. 1, 1918.

Original application filed November 5, 1915, Serial No. 59,860. Divided and this application filed September 25, 1916. Serial No. 122,061.

To all whom it may concern:

Be it known that we, MELVILLE E. PETERS, GEORGE H. FATH, and ALBERT F. MILLER, citizens of the United States of America, 5 residing at the city and county of Denver and State of Colorado, have invented a new and useful Gummed-Blank Wiper for Tight and Loose Types of Blank-Wrapping Work, of which the following is a specification.

10 Our invention relates to box and gummed blank wipers for tight and loose types of blank wrapping work for box wrapping machines; and the objects of our invention are:

First, to provide end folding wings which 15 will fold the extended ends of blanks around the corner ends of the opposite ends of boxes in both the tight and loose characters of box wrapping work, with box wrapping gummed blanks of paper or other suitable 20 materials.

Second, to provide rapid working blank 25 end and box corner and end turning and wrapping wings, of which there are two at each end of each box, which move from opposite positions simultaneously across the 30 ends of each box and when making their back or inoperative or return stroke, when gluing the blanks to the ends of the boxes, by the system known as tight wrap box 35 covering work, are moved away from the ends of the box and thus are relieved from a dragging pressure against the freshly wrapped blank and the ends of the box. While when wrapping the blank ends 40 around the ends of boxes and gluing their ends together there, by the system known as loose wrap box covering work, these same wings act exactly in reverse order, which is, that on their forward stroke across the ends 45 of a box they are held away from the ends of the box and do not bear against it, although they do bend the ends around the corners of and push the ends of the blanks around the ends of the box loosely to its center. Then when they have reached the 50 end of their forward stroke, they move directly and quickly against the ends of the box and press the gummed marginal edges

of the blanks against the ends of the box, and glue them there and they maintain a 50 resilient pressure against the ends of the blank and the box during their entire backward stroke movement.

Third, to provide a simple, quick, rapid 55 acting gummed blank and box wrapping wiper mechanism that is positioned at the opposite four corners of the gummed blanks and unwrapped boxes and that move in reciprocal horizontal planes in intermediate order following the side wrapping action of 60 box wrapping machines, which always precedes the action of these end wipers, which are adapted for both tight and loose wrap work, in which the wipers when making tight wrap work relieve themselves or back 65 off from the box on their back or inoperative stroke while the same wipers wrapping in the loose wrap kind of wrapping have an exactly reversed action.

We attain these objects by the mechanism 70 illustrated in the accompanying drawings, in which:

Figure 1 is a side elevation, partly in 75 section, of a portion of a box wrapping machine embodying our invention.

Fig. 2 is a plan view of one of the supporting standards and mechanism carried thereby for folding the end portions of the side members of a wrapper around and over the ends and corners of a box.

Fig. 3 is a central, vertical, sectional view 80 through the mechanism shown in Fig. 2.

Fig. 4 is a side elevation of a portion of the mechanism shown in Fig. 3.

Fig. 5 is a detail plan view of the operating 85 mechanism for actuating the side wiper mechanism, either for extension bottom boxes or those of the usual character.

Fig. 6 is a detail front elevation of the operating mechanism connected with the 90 upper box form plunger.

Fig. 7 is a perspective view of a partially 95 wrapped box, showing the end portions of the side members of the wrapper folded around and over the ends of a box as accomplished by our improvement.

Fig. 8 is a plan view of a tight-wrap blank or wrapper, showing the entire surface thereof coated with gum. And

Fig. 9 is a plan view of a loose-wrap blank or wrapper.

Similar letters of reference refer to similar parts throughout the several views.

Referring to the drawings:

The figures illustrate a combined blank and box corner end wiper mechanism.

Our present corner wiper mechanism is a division of our parent application for a patent for a box wrapping machine, filed November 5, 1915, Serial Number 59,860; 15 but in our present application our corner wiper mechanism is especially adapted to operate on tight wrap box and blank wrapping or covering work and also on loose wrap work. On tight wrap work its movements are in part different from its movements when wrapping with loose wrap type of blank and box wrapping or covering work.

We will then consequently describe its 25 operation and the mechanism that actuates them for both classes of wrapping work, and will describe the tight wrap class of work first.

To this end the following descriptive matter of the coöperative element and mechanism that acts prior to and handles each box and blank and brings them into such relation to each other and into a position in which our corner wiping mechanism can 35 operate on them, is given and illustrated, although this mechanism does not form a direct part of our present box corner end blank wiper mechanism, but coöperatively unites with it to perform an operative box 40 and gummed blank conveyer wrapping mechanism. A supporting bed plate 1 and a box shaped frame having side frames 2, and having a table portion 3 at their upper ends is provided.

45 Through the center of the table portion 3 of the machine, an aperture 4 is formed, in which a vertical plunger bar 5 is reciprocally mounted in adjustable slideway bearings 6 that are attached to the upper side 50 of the table portion 3 of the frame. The lower end of this bar is connected to the upper end of a cam fork 7, the lower end of which engages a cam disk 8 that is secured on the main driving shaft 9 of the machine. 55 The upper end of the plunger bar 5 is provided with a flange 10 that is secured to a block 11 of wood or other suitable material that is made of the size and width of the bottoms of the particular sizes of box that 60 are to be pressed against it. The top surface of this block is covered by a cushion of felt or other suitable material, against which the bottoms of the boxes rest.

Our plungers and size and corner mechanism will partially cover or wrap boxes of

from about 3 inches long by one inch wide by one-half inch deep, up to boxes of about 20 inches long by 12 inches wide by 3 inches deep, but each different size of box must have a plunger block 11 that will fit its outside bottom length and width dimensions, as each blank rests centrally on top of this block and each box is fed to rest centrally on the blank and to rest also centrally on the top of the block, which forms a movable support for the blanks and the boxes.

Above this lower plunger block and in vertical axial alinement with it, an upper plunger bar 12 is reciprocally mounted in suitable slideway bearings 13 that are 80 formed in an overhanging bracket arm 14 which is secured to the box frame of the machine. The lower end of this plunger bar is provided with a block 15 which we term a box form, as it is made enough 85 smaller than the box and the block 11 of the lower plunger to fit snugly inside of the boxes.

The boxes are fed automatically centrally over the top of the blanks and in that position the upper plunger's box form descends directly into the box against its bottom and presses the bottom of the box down tight against the blank and against the top of the lower plunger block. The lower plunger 95 with its block reciprocates vertically a short distance and the position in which the lower plunger block first receives the blank and the box shell is the highest point or center of its vertical reciprocal movement. Consequently when the upper plunger form descends into the box against its bottom, it instantly presses it and the blank against the block of the lower plunger, which forms an abutment to the pressure of the form of the 100 upper plunger of sufficient resistance to glue the bottom of the box to the gummed surface of the blank upon which the block rests.

The lower plunger is then drawn down by 110 its cam 8 and is forced down between the side wipers 16, and as these two plungers move down together the upper plunger which is arranged to move slightly faster than the lower plunger bears and consequently crowds down against it and thus holds the bottom with a constant pressure against the top of the lower plunger, and as the lower plunger moves slower on its down stroke than the upper plunger, the upper 120 plunger in order to yield to the slower down movement of the lower plunger, is provided with a coiled spring 17, which is mounted on a bolt 18. This bolt is provided with an eye 19 that is threaded to the upper end of 125 the bolt. This eye 19 is loosely mounted on a stud bolt 20 which is threaded into the side of the reciprocal plunger bar 12. The opposite end of the spring provided bolt is provided with a pin 21 against which a 130

washer 22 bears and the spring 17 is mounted on the bolt 18 and bears resiliently at one end against the washer and at its opposite end against the under side of one end of an eye bolt 23, that is loosely mounted on the bolt 18 and which is held under adjusted tension on the bolt by two nuts 24 which are screwed down against the eye bolt and enough further to cause the eye bolt to compress the spring until the eye bolt and the reciprocating plunger bar are under the desired tension. The eye bolt is provided with a threaded stud portion that extends loosely through and is secured by a nut to a lug 25 that forms the terminal end of a lever 26, the opposite end of which is pivotally secured to a yoke 27, that is formed on an arm portion 28 of a yoke-shaped frame 29 which rests on and is bolted to the top table portion of the box-shaped supporting frame of the machine.

The lever 26 is reciprocated vertically by a rod 30, one end of which is provided with a yoke lug 31, which straddles the rod and a pivotal bolt 32 is extended through both the lug 31 and the lever. The lever has an elongated slot 33 and the pin 32 carries a roller 34, which engages the edges of the slot, as the lever is raised and lowered, the said slot permitting the vertical movement of the rod 30, as will be understood. The opposite end of this rod 30 is connected to a lever 35, which is arranged to be engaged by a cam 36, that is formed on a disk 37, which is secured on the main driving shaft 9. This main driving shaft is positioned in the box frame above the base plate and it extends along the center of the width and throughout its length and it is journaled in boxes 38 that are secured to the base plate.

The oppositely arranged side wipers 16 that turn the upper ends of the sides of the gummed blanks up against the boxes are mounted on two stationary cross head brackets 39 that are secured to the top of the table portion of the frame, and they are arranged on opposite sides of the box supporting plungers 11 and 15. These side wipers 16 preferably consist of pieces of wood, the blank engaging faces of which are covered with strips of felt 40 or other suitable material which is glued or is otherwise secured to each wiper. These wipers are removably secured to projections 41 that are formed on cross heads 42 that are slidably mounted in slideways 43 that are formed in the brackets 39. There are two of these brackets, one on each side of the upper and lower plungers, and these two plungers reciprocally carry each box and blank between these side wipers. These side brackets are positioned parallel with the longitudinal length of the box wrapping machine, and are secured to the top of the table portion of the frame. These brackets

we term the side cross head brackets, and they each have a central standard portion 44 and two laterally extending wing portions 45, and they are of the form shown in Figs. 1, 2, 3, and 4. They each support one side and two end wrapping mechanisms. The under side of each cross head 42 is provided with a gear toothed rack portion 46, which is engaged by a toothed segment portion 47 that is formed on one end of a rock arm 48. These rock arms are pivotally secured to the brackets 39, and their opposite ends are provided with pivotal eye bolts 49, through which vertically positioned rods 50 pass loosely. A collar 51 is secured on each rod by a set screw and an expansive spring 52 is mounted on the rod between the collar and the eye bolt 49. The upper end of each rod is threaded and a collar 53 is pinned to it, which engages the eye bolt 49 on the downward movement of the rod 50.

The rods 50 extend down through bosses 54 on the brackets 39 and through the table, and rest on the ends of a bar 55, the central portion of which is secured to a vertical plunger 56, that is reciprocally mounted in a slideway formed in a transverse bracket 57, that is bolted to the sides of the frame. The lower end of the plunger bar 56, is connected by a link 58 to one end of a lever 59, the opposite end of which is rigidly secured to a shaft 60, which is mounted in a bearing standard 61, which is bolted to the bed plate. On the shaft 60 are also mounted the outer ends of lever arms 62 and 63, the inner ends of which are provided with rollers 63^A which enter respectively cam grooves in the opposite faces 64 and 65 of a cam disk 66, mounted on the cam shaft 100 95 9. Between the arms 62 and 63 and also mounted on the shaft 60, are integrally connected short arms 67 and 68, the inner ends of which are provided with holes 63^B, which are in line with corresponding holes in the arms 62 and 63. A hand lever 69 is mounted on the hub portion of the arms 67 and 68, and its forward end is pivotally attached to a locking pin 70, which is slidably mounted in the inner ends of the short arms 67 110 and 68. The locking pin is of such a length that when the lever is shifted in the direction of the arrow, the said pin projects through the hole in the arm 68 and into the hole in the arm 63, thus locking the arms 115 63 and 68 together, while the arm 62 is disconnected from the arms 67 and 68. The arm 62 and its actuating cam face 64 operate in connection with boxes of the ordinary type, while the arm 63 and its actuating cam face 65 operate in connection with boxes having extension bottoms, the respective cam grooves being arranged to that end. Thus when boxes of the usual type are being covered, the arm 63 is not needed, and when ex- 125 130

tension bottom boxes are being covered, the arm 62 is out of commission. Therefore, when boxes of the usual type are being covered, the short arm 67, which, with the arm 68, is rigidly secured to the shaft 60 by a pin or other suitable means, is locked to the arm 62, and when the arm 62 is operated by its cam 64, a corresponding movement is imparted to the short arm 67, which 10 is locked to the arm 62 by the pin 70, and as the arm 67 is rigidly connected to the shaft 60, the said shaft is turned thereby and the arm 59, which is also rigidly attached to the shaft 60, is rocked, and movement 15 is thus transmitted to the plunger arm 56 through the medium of the link 58. The arm 63 will be rocked by its cam 65, but it will perform no function as it is not locked to the shaft 60. Collars 71 are secured upon 20 the lower portions of the rods 50, and between these collars and the lower ends of the bosses 54, are interposed coiled springs 72, which act to depress the rods 50, after they have been raised and then released by the 25 cross bar 55.

The vertical movement of the rods 50 causes their collars 51 to compress the springs 52 and raise the rock arm 48, which causes the toothed ends of the rock arms 30 which engage the rack bar 46 of the cross head 42 to move the wiper blocks against the sides of the blank and box, and hold it there with a resilient tension, as the rods 50 are free to move through the eye bolts 49 after the side wiper is against the box. Consequently the side wipers bear against the box with a resiliently yielding pressure. 35

The next step treatment of wrapping the blank around the box in tight wrap work is 40 performed by the corner wipers 73. These corner wipers are used to wrap the end portions of the sides of blanks for tight wrap work that have been gummed wholly all over one of their sides, against and around 45 the corners of the box as shown in Fig. 2, just before the end wipers move into action to wrap the ends of the label against the ends of the box. There are two of these corner wipers for each end of the box, one at each 50 corner, and they each consist of a plate 73, which is provided with lugs 74 which are pivotally secured to a block 75 by a pin 76. This pin is extended beyond the lugs and a coiled spring 77 is mounted on it, one end 55 of which is secured to a collar 78 on the lower end of the pin and the other end of the spring is secured to the adjacent lug 74. Each block 75 is tiltingly secured to the end of a toothed rack bar 79 by a pin 80 and this 60 block is also tiltingly secured by a pin 81 to a similar rack bar 82. The two bars 79 and 82 are mounted parallel to each other in a slideway bracket 83 that is adjustably secured in slots 84 that are formed in each 65 end portion 45 of the bracket 39 by bolts 85,

there being two sets of these corner wipers for each side of the box. Each toothed rack bar 79 is engaged by a gear 86 that is provided with side trunnions that are mounted in bearings that are formed in the sides of 70 the slideway bracket 83. Each bracket 39 is provided with bearings 87 at its ends, in which are mounted square shafts 88 having round bushings which turn in the said bearings 87, and upon the respective shafts 88 75 are slidably mounted the gear wheels 86, two gear wheels being on each shaft. The gear wheels occupy the position shown in Fig. 2, or in other words mesh with the toothed bars 79 when tight wrap boxes are passed 80 through the machine; and for loose wrap boxes, the gears 86 are shifted to engage the toothed bars 82. The gears have short trunnions, one of which enters the opening in the adjacent side of the slideway bracket 83 85 when the gear is in mesh with the toothed bar 79, while the other trunnion enters the opening in the other side of the bracket 83 when the gear is in mesh with the toothed bar 82. The slideway is formed with a central partition web 89, which separates the toothed bars 79 and 82, the said web having a semi-circular recess to permit of the lateral shifting of the gear wheels 86. Upon the outer end of the partition web of each 90 slideway is secured a blade spring 90 having a curved portion, which, when the gear wheel 86 is in mesh with either of the toothed bars 79 or 82, is adapted to bear upon the adjacent trunnion of the said gear wheel, and thus prevent lateral shifting of the same, as will be understood by reference to Fig. 2. Each of the square shafts 88 is rotated by a gear 91 that is mounted on its forward end and which is driven by a vertically disposed toothed rack portion that is formed on a bar 92 that is slidably mounted at its upper end in slideways 93 that are formed in the adjacent ends 45 of the cross head bracket 39. The lower end of this rack 100 bar is adjustably secured to a vertically reciprocating cross head bracket 94. The slots 95 in the lower end of the rack bar when it connects with the ends of the reciprocal cross head bracket permit of vertical adjustment 110 of the rack bar.

The reciprocating bar 79 is moved by a slight throw movement of the vertical up-stroke of the cross head 94 and the vertical rack bar 92 and by its pinion 91 and the pinion 86, against the corner of the blank and the corner of the box, which throw movement is sufficient to tiltingly compress the wiper against its abutment spring as the wiper moves against and over the corner of 125 the box against its adjacent corner and edges with sufficient resilient pressure to firmly glue the corners of the blank to the corners of the box. After the corner wiper has pressed the corner of the blank against the 130

corner of the box, it is thrown back away from the box by the frictional engagement of the sliding bar 82 with its slideway, which acts to accomplish this throw movement of 5 the wiper in the following manner: The spring 77 normally holds the wiper in the position shown in Fig. 2, but the block 75 is slightly tilted on both its inward and outward movement by the frictional engagement 10 of the tooth bar not operated by the gear 86, with its slideway. In the present instance, the bar 79 is engaged by the gear 86, and the bar is moved outward or away from the box. The pull on the bar by the 15 gear wheel will cause the block to tilt outward or away from the corner of the box, owing to the consequent dragging movement of the bar 82 upon which an indirect pull is exerted. Thus when the block 75, and its 20 wiper 73 start forward or toward a box, the wiper is thrown out slightly, but the initial movement of the bar 79 tilts the block 75, owing to the indirect pull on the bar 82, and consequently the wiper 73 is pressed against 25 the end of the box. The pinion thus causes the corner wiper to tilt against the box as the wiper starts across the end corner of the box, and the bar not operated by the gear 86 causes the wiper to tilt away from the box 30 after it has completed its corner blank side end wrapping stroke. The reciprocating cross heads 94 reciprocate the rack bar 92 that rotates the pinion and shaft that through the medium of the gear 86 reciprocates the bar 79, which moves the wipers to 35 and from and across the surface of the corner ends of the box, at all four of its corners, and leaves the ends of the blank glued to the ends of the box as shown in 40 Fig. 7.

The next step treatment follows the tight wrap treatment and the final one of wrapping the blank around the box is given by the end wipers 95 which act simultaneously against the opposite ends of the label and wrap them up against and glue them to the opposite ends of the box.

The end wipers 95 are designed to engage the central portions of the ends of the 50 blanks and wipingly press them up against the ends of the box shell, and as they do this they fold and press the ends of the blanks over the corners of the blank, which have just been glued to the corners of the 55 box shell by the corner wipers. The box shell is carried down between the side and corner wipers, but the end wipers move upward against and over the ends of the opposite ends of the box shell.

60 Further description of the end wipers is not necessary, as they do not form a part of our present invention.

The mechanism that assembles the box and blank and wraps the blank to the bottom and opposite sides of each box is the

same for loose wrap work as for tight wrap work, and in the character of box wrapping work with blanks known as loose wrap work, the same arrangement of wipers is used as for tight wrap work, as the blank which 70

does not contain any adhesive gum except along its outer edge portions, as shown in Fig. 9, has to be wrapped around the box just the same, the only difference being in the operation, and in the character or dif- 75

ferent system of blank wrapping given in loose wrap work from that of tight wrap work. In tight wrap work the blank is gummed all over one side of its surface; in

loose wrap work the blank is gummed on its outside edges only and only on a portion of its end edges. In tight wrap work the blank is glued tightly throughout its surface to the box; in loose wrap work the blank is

glued only at its edges to the box, and the rest of the blank rests loosely against the bottom, the sides, and the ends of the box. In the tight wrap system the ends of the blank are pressed against and glued against 85

the opposite ends of the box on their forward stroke and are moved away from the ends of the box on their rearward or backward stroke; while in the loose wrapping the blanks are simply turned around the corners of the opposite ends of the box and

are held loosely close to the opposite ends of the box, and then at the end of their forward stroke they are moved inwardly against the opposite ends of the box, and they glue the 90

gummed edges of these loose wrap blanks to the central portion of the opposite ends of the box, and on their return or backward stroke they drag under resilient pressure against the blank and the end of the opposite ends of the box. The object of the reverse 95

relief movement of the loose wrap is simply to flatten the blank's ends close up against the ends of the box so that there will be no difficulty in properly turning the upward 100

projecting edges of these ends over the open edges of the opposite ends of the box, which is an operation that has to be done after the ends of the blank are glued to the opposite ends of the box. At the same time the rear- 105

ward sweeping pressure of the wings against the ends of the blanks presses them tightly enough against the opposite ends of the box to glue their gummed edge surfaces to the ends of the box, as it is the distinguishing 110

feature of loose wrap work that the blank throughout the inner area of its ends and also of its sides should stand smoothly close to the box but not be glued to it and thus it has what might be termed a cushioning 115

or slightly yielding feeling to the touch of the fingers, just as though there was a thin cushioning film of air between the blank and the box; while in tight wrap work the blank is glued all over to the box just as though 120

it was a part of the box itself. When 125

wrapping in the loose wrap class of work, the gear pinion 86 is shifted from the rack bar 79 as shown in Fig. 2 to the rack bar 82 by lifting the spring 90 and simply sliding it along the shaft 88. This change is all that is necessary.

The operation of the wipers is as follows: The side wipers remain up against the opposite sides of the box until while the corner and corner end wipers are wrapping the ends of the sides of the blank against the opposite corners of the opposite ends of the box, and the corner wipers in performing their wrapping functions engage the ends of the opposite sides of the blanks and fold them around and against the corner and corner edge and end portions of the opposite ends of the box, all four corner wipers operating simultaneously together.

10 These corner wipers are each preferably about a half inch wide for boxes of average height, but may be made wider or narrower if desired. As soon as the corner wipers move in contact with the blank and corner, 15 they are tilted against the corners and ends of the box, and in tight wrap work are forced to bear against them with a resilient cushioning and yielding pressure as they move inwardly on the opposite ends of the 20 box from the opposite corners of each end toward each other, and after each wiper has completed its work it is tilted backwardly 25 clear away from the ends of the box and makes its return stroke without contact 30 with the ends of the box.

The blank we preferably use for loose wrap work is illustrated in Fig. 9, and the shaded portions along its marginal edges represent all of the surface of it that is 35 coated with adhesive gum.

This loose wrapping blank is of a trifle different form from the tight wrap blank shown in Fig. 8, inasmuch as it is not provided with the inner notched corners between the sides of the blank and its ends. 40 Both the tight and loose wrapping blanks are cut out to the proper sizes to wrap around each size of boxes to be wrapped.

In loose wrap work the wipers engage the 45 ends of the sides of the blanks and carry them loosely around and over onto the ends, pushing the ends in loose contact with the opposite corners and ends of the box, and when they arrive at the end of their inner 50 blank end pushing stroke they are tilted by the rack bar 79 and pinion 86 and are forced directly against the opposite ends of the box with a resiliently cushioning and yielding pressure, which glues the gummed edges of 55 the ends of the blank tightly against the ends of the box, and they are held under this yielding cushioning pressure against the ends of the box throughout the whole of their backward or return stroke.

It will thus be seen that the wipers apply 65 wrapping pressures to the ends of the sides of the blank and to the opposite ends of the box in reverse order of operation for tight and loose wrap classes of box covering or 70 wrapping work.

Our invention provides positively operating, accurately engaging wipers that perform their work with neatness and precision, and while we have illustrated and described the preferred construction and arrangement 75 of our corner and corner end wipers, we do not wish to be limited to the construction and arrangements shown, as many changes might be made without departing from the 80 spirit of our invention.

Having described our invention, what we claim as new, and desire to secure by Letters Patent, is:

1. Box and blank corner wipers comprising suitable supporting means, a pair of reciprocating rack bars either one of which is arranged to drag the other as desired, and tilting wipers affected by said rack bars to tilt in opposite directions on their inner and outer wiping strokes as required in tight or 85 loose wrap work.

2. Box and blank corner wipers comprising reciprocating tilting wipers arranged to tilt and bear on their forward strokes and back off on their rearward strokes, and means including cam actuated gearing and resiliently tilting wipers for effecting said movement of said wipers for tight wrap blank 95 wrapping work.

3. Box and blank corner wipers comprising reciprocating and tilting wipers arranged to advance on their forward strokes at a slight distance from and clear of the ends of the boxes, and then to tilt against the ends of the blanks and resiliently press them 100 against the ends of the boxes, and means including cam actuated gearing and resiliently controlled tilting wipers for effecting these movements of the wipers in loose wrap blank 105 wrapping work.

4. In box and blank corner wipers, the combination of the supporting brackets, the rack bars reciprocally mounted therein, shafts, pinion gearing mounted thereon and meshing with said rack bars, pinions on the 110 ends of said shafts and rack bars in mesh with said pinions, and cam actuated means for operating said rack bars to operate said first mentioned pinions and wiper mechanism arranged and adapted to be reciprocated by said first mentioned pinions and rack bars for loose and tight wrap work.

5. In box and blank end wipers, the combination of the spring controlled tilting wipers, with means including vertical and 115 horizontal reciprocating rack bars and intermediate pinion connecting mechanism for reciprocally operating said wipers, said

means including cam actuated gearing operatively connected to said vertically reciprocating rack bars.

6. In box and gummed blank corner tight 5 and loose wrapping work, the combination of operative horizontally reciprocating movement wipers provided with a resiliently controlled tilting hinge movement, a block arranged to support each wiper and its hinges 10 at one end, a pair of rack bars pivoted at one end to said block, a gear arranged to be shifted from one rack bar to the other as desired, and means including cam actuated lever mechanism for operating said wipers 15 as desired to effect either tight or loose wrap work.

7. In box and blank corner and end wipers, the combination of the supporting brackets, the box and blank supporting and 20 plunger reciprocating mechanism on said supporting brackets, the block pivotally hinged to said support, the wipers pivotally hinged to said block, the shaft supported shiftable pinions mechanism, the vertical and 25 horizontal rack bars connected by said pinions, said horizontal rack bars being pivotally hinged to said blocks, and means including the cam operated mechanism for reciprocating said vertical rack bars.

8. Box and blank corner wipers for tight 30 and loose wrap work, comprising supporting mechanism, reciprocating wipers arranged to engage the corners of blanks on their inner reciprocal strokes for tight 35 wrap work and to back off on their return stroke on tight wrap work, and that will advance on their forward stroke without pressing the ends of the blank against the corners and ends of the box, but will move 40 against and press the ends of the blanks against the ends of the box and will continuously exert pressure against the ends of the blanks and the end of the box on their return reciprocal stroke movements for loose 45 wrap work, said mechanism comprising means including a pair of differently moving rack bars and a shifting gear and cam and lever mechanism for operating the same to effect either class of wrapping work when 50 desired.

9. The combination of the frame, the supporting brackets secured to said frame, the vertical and horizontal rack bars reciprocally mounted in said brackets, with the 55 square shaft journaled in said brackets, the gears slidably mounted thereon and arranged to mesh with said vertical and horizontal rack bars, and arranged to be moved on said square shaft from one rack bar 60 to another, with the resiliently supported wipers arranged to be operated by said rack bars and gears to effect both tight and loose wrap work as desired.

10. The combination of the supporting

box frame provided with the upper and 65 lower blank supporting plungers and their operating mechanism, the wiper supporting brackets secured to said frame, means for adjusting said brackets to and from said plungers, the wiper mechanism slidably 70 adjustable on said brackets to fit boxes of different sizes, said wiper mechanism comprising suitable blank corner engaging wiper members, a supporting block pivotally hinged to each wiper, a spring arranged 75 at the hinge end secured to said block and wiper to hold each wiper under a blank engaging resilient pressure, a pair of rack bars at each end of each wiper supporting brackets, each rack bar of each pair being 80 pivotally connected at one end to said block in such a manner that when one rack bar is moved it tilts the block and moves the other rack bar to follow the movement of the moved rack bar which tilting movement of 85 said block also tilts the wiper pivoted to it and means including a gear slidable laterally from one rack bar to the other, and including cam actuated lever controlled gearing for operatively reciprocating said rack 90 bars.

11. The combination with a frame and standards mounted thereon, which are adjustable toward and away from each other, 95 of pairs of brackets mounted on said standards, the brackets of each pair being adjustable toward and away from each other in directions at right angles to the direction of movement of the standards, slidable elements in said brackets, spring-pressed 100 wipers pivotally connected to said sliding elements, and means for reciprocating said sliding elements, said sliding elements being arranged to effect an inward tilting of 105 the wipers in one direction of their movement, and an outward tilting in the opposite direction of movement.

12. The combination with a frame and standards mounted thereon which are adjustable toward and away from each other, 110 of pairs of brackets mounted on said standard, the brackets of each pair being adjustable toward and away from each other in directions at right angles to the movement of the standards, a pair of rack bars slidably mounted in each bracket, a block pivotally connected to each pair of rack bars, a spring pressed wiper on each block, a shiftable pinion for engaging one or the other rack bar in each pair, and means for operating all of said pinions simultaneously. 115

13. The combination with a frame and standards mounted thereon and adjustable toward and away from each other, of pairs of brackets adjustably mounted on the 120 standards, to be moved toward or away from each other at right angles to the movement of the standards, a pair of rack bars slidably

mounted in each bracket, a block pivotally connected to each pair of rack bars, a spring pressed wiper pivotally connected to each block, a shaft mounted in each standard above the rack bars, gears slidably but non-rotatably mounted in said shafts and adapted to mesh with one or the other rack bar in each pair, and a cam operated rack and pinion mechanism for rotating said shafts.

In testimony whereof we affix our signatures in presence of two witnesses.

MELVILLE E. PETERS.
GEORGE H. FATH.
ALBERT F. MILLER.
